ELECTRICAL SOCKET

Archie R. Wolfe, Summit, N. J.

Application June 27, 1929. Serial No. 374,198.

5 Claims. (Cl. 173—358)

Granted under the act of March 3, 1883, as

amended April 30, 1928; 370 O. G. 757.

My invention relates to improvements in electric light sockets adapted to attach and electrically connect and detach and disconnect the standard screw rim electric light plug or lamp without screwing the latter or said socket, and the objects of my improvements are, first, to provide in such a socket a means for assuring electrical connection between the center contact of the latter and the center contact of any standard screw rim plug or lamp that may be connected to said socket, by vertically reciprocating the center contact of the latter; second, to afford facilities in such a socket for operating a vertically movable center contact in combination with a means for attaching and a means for detaching the screw rim of any standard screw rim plug or lamp without screwing, for depressing said center contact a certain distance before said plug or lamp can be attached and for elevating said center contact a suitable distance under spring pressure after said plug or lamp has been attached; third, to provide facilities for operating all of the mechanism of said socket by a single means on the outside of the latter; fourth, to produce a socket that may be readily designed for use in dining room chandelier fixtures in the home and for electric lighting fixtures in general; and fifth, to produce such a socket adapted to carry larger electric currents than a Cam lock contraction socket described in my Patent No. 1,810,455, issued June 16, 1931, and of lower cost manufacture than a Simplex contraction socket described in my Patent No. 1,770,377, issued July 15, 1930.

One form of my invention is illustrated in the accompanying drawing, in which, Fig. 1, is a view of the invention from a point vertically above the center of its upper end; Fig. 2, is a vertical sectional view on the broken line 2—2, Fig. 1; Fig. 3, is a plan view of the upper side of the cam 34, and its insulation handle 33, affixed thereto; Fig. 4, is a vertical sectional view on the broken line 4—4, Fig. 1; Fig. 5, is a view of the upper end of the lower section 3, of the insulation body, with all mechanism removed and detached from said invention; Fig. 6, is a view of the cylindrical shell 1, detached from said invention; Fig. 7, is a view of the outer face of the lever jaw spring 19, as detached from said invention; Fig. 8, is a view of the inner face of the lever jaw 9, as detached from said invention; Fig. 9 is a perspective view of center contact and clamping jaws; and Fig. 10 is a side view of Fig. 3.

Similar numerals refer to similar parts throughout the several views.

The shell 1, upper section 2, of the insulation

body and lower section 3, of the insulation body are rigidly clamped together by the metal tie bolts 4, and 5. Said bolt 4, is threaded to a nut countersunk into the bottom of said section 3, and bolt 5, is threaded to the shell terminal post 6. Said shell 1, is adapted to accommodate the screw rim of any standard screw rim electric light plug or lamp without screwing and is provided with the bearing apertures 7, and 8, which serve as fulcrum bearings for the lever jaws 9, and 10, respectively. The inner face of each of said jaws is provided near its upper end with ribs or threads which are adapted to engage the threads on the screw rim of the standard plug or lamp. The shoulders 11, and 12, on said jaws 9, and 10, respectively, limit the downward movement of the latter and the flanges 13, and 14, respectively, on said shell 1, limit the upward movement of said jaws after said socket is assembled.

Said jaws 9, and 10, project downward through 75 said apertures 7, and 8, and the apertures 15, and 16, in said section 2, and into the cavities 17, and 18, respectively, in said section 3. The lever jaw springs 19, and 20, are attached to said jaws 9, and 10, respectively, and tend to keep the latter 80 in the inner position as shown in Figs. 1, 2, and 4. The spring metal center contact 21, projects downward through the aperture 22, in said section 2, and into the slotted cavity 23, in said section 3, where its lower end is secured to said section 3, 85 by the metal screw 24, which also secures the center contact terminal post 25, to said section 3. Said center contact 21, is provided with the flange 90 bearings 26, and 27, to which is hinged the upper end of the insulator 28. The lower end of the latter is hinged to the metal guide 29, which is provided with the rectangular cam apertures 30, and 31, and is vertically reciprocable in the slot 32, in said section 3.

The insulation handle 33, is rigidly affixed to the outer end of the horizontally reciprocable metal cam 34, which is provided with two prongs which straddle said lever jaw 9, and project into the cavities 35, and 36, in said section 3, and into 95 said cam apertures 30, and 31. The inner ends of said prongs are provided with a similar cam surface sufficiently inclined from the vertical to engage the lower ends of said apertures 30, and 31, and actuate said guide 29, and consequently said insulator 28, and said center contact 21, downward a certain distance against the spring tension of the latter when said cam 34, is manually moved inwardly by means of said handle 33. And when the latter is released the spring tension of said center contact 21, elevates the upper end of the 100 105 110

- latter, said insulator 28, and guide 29. And the latter acting on the cam surfaces of said prongs moves said cam 34, and consequently said handle 33, outwardly to their original position. The outward movement of said cam 34, is limited by the stops 37, and 38, which project from said spring 19, into the slots 39, and 40, respectively, in said cam 34, and the inward movement of the latter is limited by said lever jaw 9.
- 10 The insulated handle 41, is secured to said lever jaw 10, and projects on the outside of said section 3, through an aperture provided in the latter. The practical operation of the invention is briefly described as follows:
- 15 Beginning with the mechanism in the position as shown in Figs. 1, 2, and 4, the handles 33, and 41, are grasped by a thumb and forefinger of one hand and moved inwardly or toward each other as far as they will go. During the latter movement the handle 33, first moves the cam 34, into engagement with the guide 29, which lowers or depresses the latter together with the insulator 28, and center contact 21, a maximum distance against the spring tension of the latter. Said cam 34, then collides with the lever jaw 9, requiring an additional force to be applied on said handles 33, and 41, which simultaneously moves the lever jaws 9, and 10, away from each other, a maximum distance against the tension of the springs 19, and 20. A plug or lamp may now be inserted in said socket 1, as far as it will go with gentle pressure. Said handles 33, and 41, are then released, which first, permits said springs 19, and 20, to move said jaws 9, and 10, toward each other, securing the latter to the screw rim of said plug or lamp; and second, permits the self contained spring in said center contact 21, to elevate the latter until it collides and makes contact with the center contact of said plug or lamp.
- 25 To detach and disconnect said plug or lamp from said socket again press said handles 33, and 41, toward each other as far as they will go and withdraw said plug or lamp from said shell 1.
- 30 The invention described herein may be manufactured and used by or for the Government of the United States for governmental purposes without the payment to me of any royalty thereon.
- 35 I claim:
- 50 1. In an electrical socket, the combination of a reciprocating center contact having one end secured to the body of the socket, a vertically mov-
able insulated base member supporting said contact intermediate its fixed and free ends, means mounted in the socket for securing an electrical appliance thereto, and means carried by the socket for simultaneously operating said base member and attachment securing means. 80
- 55 2. In an electrical socket, the combination of a reciprocating center contact having one end secured to the body of the socket, a vertically mov-
able insulated base member supporting the center contact intermediate its fixed and free ends, means mounted within the socket for securing an electrical appliance thereto, means normally holding the clamping ends of said first means in an inner position, and means for sub-
stantially simultaneously and independently op-
erating the center contact support and moving the clamping ends of said attachment securing means to an outward position. 85
- 60 3. In an electrical socket, the combination of a movable center contact, a vertically movable insulated base member supporting said contact, a guide member provided with openings, carried by said base member, means mounted within the socket for securing an electrical appliance thereto, and means engaging in said openings in the guide member for operating the center contact and with the attachment securing means for op-
erating the same. 90
- 65 4. In an electrical socket, the combination of a movable center contact secured at one end to the socket, a vertically movable insulated base member supporting the center contact interme-
diate its ends, means mounted within the socket for securing an electrical appliance thereto, and means extending without the socket for en-
gaging with the base member and attachment securing means for their substantially simultaneous operation. 100
- 70 5. In an electrical socket, a body member, a shell mounted thereon, a movable center contact secured at one end to the socket, a vertically movable insulated base supporting the free end of the center contact, clamping members ful-
crumed through the shell, means normally hold-
ing the clamping ends of said members within the shell, and slidable means for simultaneously de-
pressing said contact and outwardly moving said clamping ends. 105
- 75 1. In an electrical socket, the combination of a reciprocating center contact having one end secured to the body of the socket, a vertically mov-
able insulated base member supporting said contact intermediate its fixed and free ends, means mounted in the socket for securing an electrical appliance thereto, and means carried by the socket for simultaneously operating said base member and attachment securing means. 110
- 80 2. In an electrical socket, the combination of a reciprocating center contact having one end secured to the body of the socket, a vertically mov-
able insulated base member supporting the center contact intermediate its fixed and free ends, means mounted within the socket for securing an electrical appliance thereto, means normally holding the clamping ends of said first means in an inner position, and means for sub-
stantially simultaneously and independently op-
erating the center contact support and moving the clamping ends of said attachment securing means to an outward position. 115
- 85 3. In an electrical socket, the combination of a movable center contact, a vertically movable insulated base member supporting said contact, a guide member provided with openings, carried by said base member, means mounted within the socket for securing an electrical appliance thereto, and means engaging in said openings in the guide member for operating the center contact and with the attachment securing means for op-
erating the same. 120
- 90 4. In an electrical socket, the combination of a movable center contact secured at one end to the socket, a vertically movable insulated base member supporting the center contact interme-
diate its ends, means mounted within the socket for securing an electrical appliance thereto, and means extending without the socket for en-
gaging with the base member and attachment securing means for their substantially simultaneous operation. 125
- 95 5. In an electrical socket, a body member, a shell mounted thereon, a movable center contact secured at one end to the socket, a vertically movable insulated base supporting the free end of the center contact, clamping members ful-
crumed through the shell, means normally hold-
ing the clamping ends of said members within the shell, and slidable means for simultaneously de-
pressing said contact and outwardly moving said clamping ends. 130
- 100 1. In an electrical socket, the combination of a reciprocating center contact having one end secured to the body of the socket, a vertically mov-
able insulated base member supporting said contact intermediate its fixed and free ends, means mounted in the socket for securing an electrical appliance thereto, and means carried by the socket for simultaneously operating said base member and attachment securing means. 135
- 105 2. In an electrical socket, the combination of a reciprocating center contact having one end secured to the body of the socket, a vertically mov-
able insulated base member supporting the center contact intermediate its fixed and free ends, means mounted within the socket for securing an electrical appliance thereto, means normally holding the clamping ends of said first means in an inner position, and means for sub-
stantially simultaneously and independently op-
erating the center contact support and moving the clamping ends of said attachment securing means to an outward position. 140
- 110 3. In an electrical socket, the combination of a movable center contact, a vertically movable insulated base member supporting said contact, a guide member provided with openings, carried by said base member, means mounted within the socket for securing an electrical appliance thereto, and means engaging in said openings in the guide member for operating the center contact and with the attachment securing means for op-
erating the same. 145
- 115 4. In an electrical socket, the combination of a movable center contact secured at one end to the socket, a vertically movable insulated base member supporting the center contact intermediate its ends, means mounted within the socket for securing an electrical appliance thereto, and means extending without the socket for en-
gaging with the base member and attachment securing means for their substantially simultaneous operation. 150
